UNITED STATES PATENT OFFICE.

ERROLL M. AUGUR, OF NEW HAVEN, CONNECTICUT.

SHOE HEEL.

Application filed January 10, 1922. Serial No. 528,281.

To all whom it may concern:

Be it known that I, ERROLL M. AUGUR, a citizen of the United States, residing in the city and county of New Haven, State 5 of Connecticut, have invented certain new and useful Improvements in Shoe Heels, of which the following is a full, clear, and exact description.

My invention relates to shoe heels and 10 more particularly to a heel which is to be manufactured as a unit and thereafter applied to the sole of a shoe. The heels of shoes, and more particularly those of ladies' shoes, are very apt to become broken and 15 it is then necessary to replace them with a new heel. In such case, it is highly desirable to provide a unitary heel structure which is complete in every detail and which may be readily attached to the sole of the 20 shoe to replace the broken structure.

Moreover, it is sometimes desirable to provide such a heel for the use of manufacturers of shoes as well as for the use of cobblers or shoe repairers and my improved heel will 25 be found to be just as readily applicable to a new shoe in the process of manufacture as to one from which the heel has been broken.

In applying heels of this character to shoes, it is sometimes difficult to locate them 30 properly in the first instance and it is sometimes necessary to remove the fastening devices and adjust them to a different position. This disadvantage will be obviated if a heel is provided which after being attached to 35 the shoe may be adjusted to some extent to the proper position before it is firmly secured in position.

One object of my invention is to provide a unitary heel which may be easily and conveniently applied in proper position upon 40 the sole of a shoe.

A further object of my invention is to provide a shoe heel which may be capable to adjustment relatively to the sole of a shoe 45 and when in proper position may then be firmly secured in place without danger of its becoming dislodged from this position.

A still further object of my invention is to provide a heel of this character which 50 may be adjustably secured to the shoe and may at the same time be secured so firmly and readily in position that there will be no danger of its becoming lost or its being kicked off.

55 A still further object of my invention is to provide a new and improved heel of cast

metal such as aluminum having means for adjustably securing it to a shoe so that prior to the tightening of the securing members to fix the heel in position, the same may be adjusted relatively to the shoe sole so that it may thereafter be secured in the proper position, and which shall be economical to manufacture, satisfactory in its wearing qualities and capable of easy and firm attachment to the shoe heel. In some aspects of the invention my improvements are not limited to a metallic heel, but will be applicable to heels of various types regardless of the material from which they are made. 60 65 70

To these and other ends, the invention consists in the novel features and combinations of parts to be hereinafter described and claimed.

In the accompanying drawings:

Figure 1 is a sectional view of the rear portion of a shoe provided with a heel embodying my improvements.

Figure 2 is a sectional figure on line 2—2 of Figure 1.

Figure 3 is a sectional view on line 3—3 of Figure 1.

Figure 4 is a sectional view similar to Figure 1, showing my improvements applied to what is known as a Cuban heel.

Figure 5 is a sectional view on line 5—5 of Figure 4.

Figure 6 is a bottom view of the attaching plate used in Figures 1 to 3.

Figure 7 is a view similar to Figure 6 of 90 the plate used with the Cuban heel shown in Figures 4 and 5.

In illustrating my invention, I have shown a portion of a shoe comprising the sole 10, the upper 11 and an insole 12. As shown 95 in Figure 1, the upper of the shoe is joined to the sole at the upper surface thereof and below the insole 12, in the usual manner.

My improved heel structure comprises a body portion 13 which may preferably be 100 cast of a suitable light metal such as aluminum or the like and as shown in the drawings may be hollow and present an upwardly facing top cavity 14. The bottom of the heel may be provided with a bottom cavity 15 in which is positioned the upper reduced portion 16 of a suitable lift 17 which is secured to the shoe by means of the screw 18. Between the edges of the cavity 15 and the lift 17 may be inserted a metallic plate 110 19 to carry the weight of the wearer from the lift.

To provide suitable means for attaching the heel to the shoe, I have shown upstanding lugs 20 and 21 extending laterally into the cavity 14 which lugs may preferably be cast integrally with the shoe. These lugs as shown are provided with slots 22 and 23 extending longitudinally of the heel to provide the ledges 24 and 25 which extend laterally into the cavity and which are particularly important in connection with the means used to secure the heel in position. If desired, these ledges may be provided at the sides of the shoe heel in other ways but I have preferred to use the side lugs provided with these ledges so as to strengthen the sides of the structure. As illustrated in the drawings, shoulders 26 and 27 are formed at the bottom of the slots 22 and 23 but these may be dispensed with if desired as it will be noted that these shoulders do not form a part of the means of attaching the heel as do the upper ledges 24 and 25.

Below the inwardly projecting ledges and slidably received in the slots 22 and 23 is a retaining member in the form of a plate 28 which is provided with threaded openings 29 and 30 to receive the screws 31 and 32 which are passed through openings 34 and 35 provided in an attaching plate 36 disposed within the shoe between the insole 12 and the sole 10. As will be obvious, these screws pass also through the sole of the shoe and the lower ends thereof are threaded into the openings 29 and 30 in the plate 28. The screws are provided with enlarged heads of the usual form which are adapted to seat in counter-bores or depressions 37 and 38 in the upper surface of the plate 36. It will be apparent that when the plate 36 is placed within the shoe and the screws are passed through the plate and through the shoe sole and threaded into the plate 28, the heel will be securely clamped upon the shoe the plate member bridging the cavity 14 and is slidably within the slots 22 and 23 so that after the screws are threaded into the plate the heel may be adjusted to some extent longitudinally of the shoe prior to the tightening of the screws securely in place. When the screws are tightened, the plate member 28 will be drawn upwardly against the ledges 24 and 25 to securely hold the heel in proper adjusted position upon the shoe.

Although it will not always be found necessary to do so, I have shown the opening 39 in the forward portion of the heel which may receive the nail or peg 40 passing into the shoe sole provided the additional securing means after the heel has been properly positioned upon the shoe is secured in this manner. The heel, while firmly held against accidental displacement and detachment from the shoe may be readily taken off when it is desired to replace it with another heel.

In Figures 4 and 5, I have shown my improvements applied to a heel of another shape commonly known as a Cuban heel, the shape shown in Figures 1 to 3 being ordinarily referred to by the term French heel. In this form, I have shown a heel body 41 provided with an upwardly facing cavity 42 and a bottom cavity 43 in which is mounted a lift designated as a whole by the numeral 44 and which may be of the character described in connection with Figures 1 to 3. Upon the sides of this heel are provided the lugs 45 and 46 having the slots 47 to provide the overhanging and inwardly projecting ledges 48 with which the plate member 49 is adapted to engage when drawn toward the shoe sole 10 by the fastening members or screws 50 and 51 pass through the sole and through openings 52 and 53 provided in a plate 54 positioned within the shoe as described in connection with Figures 1 to 3. This heel while differing in shape from the one shown in the former figures is secured to the shoe in the same manner and is capable of the same adjustment and the same ready application as the one described above. With this modification, it may not be necessary to use any fastening member corresponding to the nail or peg 40 shown in Figure 1 as the Cuban heel is somewhat shorter than the French heel at its upper portion and this additional fastening member may be dispensed with. If found expedient, it may, however, be used without departing from the principles of my invention.

It will be apparent that I have provided an improved heel which is extremely light in weight and which at the same time may be readily applied to the sole of a shoe and adjusted to its proper position prior to being finally secured in place. Moreover, I have provided a heel which is extremely economical to manufacture in that it may be cast as an integral structure and be held in position upon the shoe principally by friction or binding force between the plate 28 and the ledges 24 and 25 formed integrally with the body of the heel.

While I have shown and described some preferred embodiments of my invention, it will be understood that the same must not be limited to the exact details shown but is capable of many modifications and variations which lie within the spirit of the invention and within the scope of the appended claims.

What I claim is:

1. In a heel structure, a metal body having a top cavity, oppositely disposed lugs, provided on the sides of the body, having slots therein extending longitudinally of the heel, a member adjustably mounted in the slots and spanning the cavity, and fastening members designed to be secured to the shoe

and to said member at spaced points transversely of the heel, said lugs being relatively short and having the slots opening through the edges thereof to admit said member.

5 2. In a heel structure, a body having a top cavity, means projecting laterally into the cavity and providing longitudinally extending oppositely disposed slots at the sides of the body, a retaining member slidably received in said slots and spanning the cavity, and fastening members designed to be secured to the shoe and to said member, said retaining member extending transversely entirely across the heel, said slots opening 10 into the heel cavity to permit the insertion 15 of said retaining member thereinto.

3. A shoe heel having a top cavity, and ledges provided on the sides thereof projecting laterally into the cavity, a movably mounted member bridging the cavity and having its opposite ends positioned below said ledges and means for securing said member to a shoe to clamp the heel thereon, said ledges being relatively short compared to the length of the heel cavity and being 20 positioned at the intermediate portion of the heel in a lengthwise direction to permit the positioning of the member therebelow at the ends thereof.

In witness whereof, I have hereunto set 30 my hand this 6th day of January, 1922.

ERROLL M. AUGUR.
